UNITED STATES PATENT OFFICE.

MORRIS BERNHARD, OF NEW YORK, N. Y.

HANGER.

Application filed February 12, 1926. Serial No. 87,839.

This invention is an improvement in hangers for pictures, mirrors and the like, and more particularly in mechanism for rigidly connecting the several parts of a hanger 5 rosette, including the supporting hook and ornament.

Hangers of the character in question are used in connection with picture hanging, for supporting the pictures from a picture rail, 10 or a fixed object in the wall, as for instance a nail. The device for engaging the rail or fixed support is at the rear of a rosette, which forms an ornamental facing covering and concealing the hanging means.

15 The picture is supported usually from a hanger, that is, from a mechanism which engages the rail or the fixed support, by means of a cord or the like, and the connection between the hanger and the rosette is 20 usually very loose in nature so that the rosette does not always occupy, and does not retain, a definite fixed position with respect to the hanger.

25 The hanger rosettes as usually constructed are composed of a body or button of ornamental character and suitably covered, a border, and the hanger. The supporting cord for the picture is connected with the hanger and usually an ornamental tassel is 30 provided in connection with the cord.

35 One of the primary objects of this invention is the provision of a hanger of the character specified, wherein the parts are rigidly connected, so that all occupy a definite fixed 40 position with respect to each other.

Another object is the provision of a backing 45 for the rosette of hangers of the character in question, of a nature such that it may be quickly and rigidly secured to the rosette body in a manner to hold the border 50 in clamped relation.

Another object is the provision of a backing having means for rigidly connecting a hook or other supporting means for the rosette to one face thereof, and having other means enabling the quick connection of the backing to the rosette body.

55 Another object is to provide a backing of the character above specified having means to engage the border to prevent angular movement thereof with respect to the button or body, and of a size relative to the button or body to clamp the inner edge of the border between the button and the body.

55 With these and other objects in view, the invention consists in the construction and

novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

65 In the drawings forming a part hereof:

Fig. 1 is a perspective view of the improved hanger looking from the rear.

Fig. 2 is a section on the line 2—2 of Figure 1.

Fig. 3 is a perspective view of the hanger with the parts separated.

Fig. 4 is a section on the line 4—4 of Figure 2.

Fig. 5 is a front view having an alternative construction of border engaging means.

Fig. 6 is a perspective view showing the backing connected with an alternative construction of hanger.

70 In the embodiment of the invention shown in Figures 1—4 inclusive, the rosette includes the button or body 1, of circular form and covered with suitable ornamental material as shown. The border 2 is ring shaped and of a netted nature, and is of a size as regards its inner diameter less than the overall diameter of the button, the external diameter being greater than that of the button, so that when the border is placed against the rear flat face of the button, the outer edge thereof will extend beyond the button, 75 as indicated in Figure 1.

75 The backing consists of a plate or disk 3, of a diameter slightly less than the diameter of the button, and is of a semi-rigid material, such for instance as sheet metal. The disk has openings 4, preferably arranged upon a diameter thereof, through which may be passed securing means 5, such for instance as tacks. On one face the backing has lugs 6 which may be formed by cutting through the material of the backing in the manner shown, and bending up the portions of the material between the cuts.

80 These lugs 6, are adapted to be bent over upon the suspending means or hanger proper, hereafter designated as a hook, to secure the same to the backing. In the present instance the hook includes substantially parallel members 7, connected at one end by a hook portion 8, and provided at the other end with aligned rings 9, with which a picture

cord 10 may be engaged as shown in Figures 1 and 2. With this construction of hook, the lugs 6 are bent about the members in the manner shown in Figure 4 thus rigidly clamping the hook to the backing.

The relative size of the button and backing are such that when the border is placed on the button as previously mentioned, and the backing is placed thereover concentric with the button, the inner edge of the border will be clamped between the backing and the button. The insertion of the securing means 5 will then rigidly connect backing, button, border and hook.

15 In order to prevent pulling out of any part of the border with respect to the other parts, I provide spurs or lugs 11 at the edge of the backing. These spurs are pointed as shown, and bent in the opposite direction to the lugs 6. When the backing is placed on the border and button, the spurs extend through the meshes of the border into contact with the button.

20 In Figure 5 there is shown an alternative method of connecting the border. In this construction the backing 12 which is substantially the same as that shown in Figure 3, has the struck-up lugs 12^a corresponding to the lugs 6 of Figure 4, for securing the hook, indicated generally at 13, thereto. The backing also has the openings 14 for the securing means, such as tacks or screws.

25 The backing is provided with struck-up spurs 15 at its edge, said spurs being arranged in pairs as shown, in the present instance four pairs being provided. The spurs extend through the meshes of the border 16 and are bent over the meshes or other parts of the border as shown, the members of each pair being preferably bent toward each other. Thus the border is held closely to the backing.

30 In Figure 6 another form of hook is shown, the said hook being formed from a plate 17 of metal having each of its ends bent in opposite directions to form hook portions 18 and 19 respectively. The backing 20, similar to the backing 3 of Figure 3 has the lugs 21 corresponding to the lugs 6. The body of the hook is placed between the lugs, which are then bent over up on the body, thus firmly securing backing and hook together. The backing may be of the character shown in Figure 3, or of the character shown in Figure 5. In this form of hook, the hook portion 18 is adapted for connection with the cord 10. As shown in Figure 1, an ornamental tassel 22 is usually arranged on the cord just below the hook, and it is obvious that this tassel may be of any usual or desired construction, and of any suitable material. Preferably it will harmonize in material, color and the like with the rosette.

35 The invention contemplates marketing the device as the improved backing shown in

Figure 3, in the backing and connected hook as shown in Figure 4, in the backing, hook and rosette border as shown in Figure 5, in the backing border and button, that is the backing and rosette, and in the completed article shown in Figure 1. It is obvious that the backing in the form shown in Figure 3 is adapted for sale to manufacturers and assemblers of the rosettes. It is equally well adapted for such sale in the forms shown in Figures 4 and 6.

40 As a completed rosette the article will be marketed for assembling with cords and tassels. With the border attached to the backing in the form shown in Figure 5, the assembling of the parts is facilitated. Borders of different character will be furnished with backings having hangers attached, to be assembled with rosettes cords and tassels of any desired make.

45 I claim:

1. As an article of manufacture, means to connect a rosette including a border to a hook hanger, comprising a plate having on one face integral means to rigidly connect the plate to the hook hanger, and provided at the opposite face with lugs near the periphery thereof to extend through the meshes of the border to contact with the rosette body, the plate having means whereby it may be secured to the body to clamp the border between the body and the plate.

50 2. As an article of manufacture, a common means to rigidly connect the body and the border of a rosette to each other and to a hanger, comprising a plate having means at one face to rigidly connect the hanger thereto, and of a size to clamp the edge of the border between the other face of the plate and the body, and having on the said face means to engage the border to prevent angular movement thereof, said plate having a plurality of openings to receive tacks or the like to connect the plate to the body.

55 3. As an article of manufacture, a common means to rigidly connect the body and the border of a rosette to each other and to a hanger, comprising a plate having means at one face to rigidly connect the hanger thereto, and of a size to clamp the edge of the border between the other face of the plate and the body, and having on the said face means to engage the border to prevent angular movement thereof, said plate having a plurality of openings to receive tacks or the like to connect the plate to the body, the first named means comprising bendable lugs extending from the plate face and adapted to be bent about the hanger to clamp the same to the plate.

60 4. As an article of manufacture, a common means to rigidly connect the body and the border of a rosette to each other and to a hanger, comprising a plate having means at one face to rigidly connect the hanger

thereto, and of a size to clamp the edge of the border between the other face of the plate and the body, and having on the said face means to engage the border to prevent 5 angular movement thereof, said plate having a plurality of openings to receive tacks or the like to connect the plate to the body, the last named means comprising spurs extending laterally from the plate at the edge 10 thereof.

5. As an article of manufacture, a rosette including a body and a radially extending border, and a plate of semi-rigid material secured to the body and clamping the border thereto, and having means extending through the meshes of the border, to prevent relative movement of border and plate, the plate having means to rigidly connect a hanger thereto.

20 6. As an article of manufacture, a rosette including a body, a hook hanger, and a plate connecting the hanger and the body, and rigidly connected to both hanger and body, and a border having its edge received between the plate and the body, and clamped in place between the plate and body, the plate having means to prevent angular movement of the border with respect to the 25 rosette.

30 7. As an article of manufacture, a rosette including a body, a hook hanger, and a plate connecting the hanger and the body, and rigidly connected to both hanger and body,

and a border having its edge received between the plate and the body, and clamped 35 in place between the plate and body, the plate having means to prevent angular movement of the border with respect to the rosette, said means comprising spurs near the edge of the plate adapted to engage the 40 meshes of the border.

8. A hanger for pictures and the like, including a rosette, a border for the rosette, and a hanger element, and a rigid means between the hanger element and the rosette 45 and clamping the border to the rosette, said means comprising a plate of substantially rigid material having means to rigidly connect the hanger element thereto, and other means whereby it may be secured to the 50 rosette.

9. A hanger for pictures and the like including a rosette, a hanger element having a hook to engage a molding or the like and means for engagement by a suspending cord, 55 and a substantially rigid plate between the hanger element and the rosette provided with lugs for permanently connecting the hanger element thereto, and with means for connecting the plate to the rosette, the rosette of a size to conceal the plate and the hanger element.

Signed at New York in the county of New York and State of New York this 11th day of February A. D. 1926.

MORRIS BERNHARD.
